UNITED STATES PATENT OFFICE.

RICHARD VREELAND, OF BAYONNE, NEW JERSEY, AND JAMES F. LEAHY, OF BROOKLYN, NEW YORK.

IGNITION DEVICE.

Application filed November 17, 1927. Serial No. 233,810.

This invention relates to ignition devices for internal combustion engines and has for its object to improve the conditions under which ignition takes place; to enable an engine of this character to be operated more economically; and to render it more effective.

One of the objects of our invention is to provide an improved mount for spark plugs whereby the sparking terminals may be arranged in a chamber wherein pressures substantially at or near atmosphere may be maintained, thus making it possible to secure longer spark-gaps and to use leaner mixtures 15, where desired.

Another object of the present invention is to provide an improved attachment whereby spark plugs of usual construction may be connected up to the cylinder of an internal combustion engine for the purpose of securing the advantages referred to above.

Other and further objects of invention will appear in the specification, the novel features related thereto being recited in the 25 claims.

The principle of our invention is exemplified in the drawings, in which

Figure 1 is an axial section of one embodiment of our invention according to which a 30 spark plug of well-known type is mounted in an improved relation to the cylinder of an internal combustion engine as hereinafter described.

Figure 2 is a similar axial section showing 35 a modified use of our improved device with other parts.

Figure 3 is a detail section on the line 3—3, Figure 1.

Figure 4 is a perspective view of the ball- 40 valve yoke detached.

According to the preferred embodiment of our invention shown in Figure 1 of the drawings, a housing 1 for the terminal end of a spark plug is provided with a tubular neck or extension 2 adapted to be threaded into a wall 3 of a cylinder of an internal combustion engine. The inner wall of tubular extension 2 is provided with screw-threads 4 adapted to inter-engage with the 45 oppositely threaded portions 5, 5 of a yoke, shown best in Figure 4, and comprising an annulus 6 at one end, connected by laterally spaced arms 7, 7 to a cross-piece 8. As 50 shown in Figure 3, the arms 7, 7 are provided with concaved inner edges to form a suitable ball race for one or more balls 9 which are thereby suitably arranged to be moved to and fro with respect to a port-opening 10 formed in the bottom wall of the housing 1 and arranged to permit the passage of gases between an ignition chamber 11 formed within the housing 1 and the space formed within the bore of the plug or extension 2. The proportioning of parts around the port opening 10 is such that 60 when the balls 9 are in their position of rest, said port opening is restricted and partially throttled by said balls. If desired, the cross-piece 8 of the yoke may be provided with a port-opening 12 to afford a 70 more direct line of pressure between the interior of the cylinder 3 and the ignition chamber 11. A spark plug 13 of well-known type may be employed with our improved connection, said spark plug being 75 provided with a threaded portion 14 adapted to be screwed into the upper wall of housing 1 in such a way as to bring the sparking terminals 15 and 16 within the ignition chamber 11. Said spark plug is provided 80 with a lead wire 17. If desired, the housing 1 may be provided with an aperture 18 which is closed by a glass disc 19, an annular nut 20 being threaded into the adjacent wall of said housing to retain the glass 85 19 in position. By means of this device, the action of the sparking terminals 15 and 16 may be observed for the purpose of regulating the operation of the ignition device, richness of mixtures, etc. A second port-opening 90 21 may be provided to connect the ignition chamber 11 with the outside atmosphere, the function of this port being to prevent, where required, a rise of pressure within the chamber 11. Ordinarily, however, it 95 is preferable to have the port-opening 21 sealed by means of a threaded plug 22. Under these conditions, the pressure in chamber 11 will rise in a slight degree only above atmosphere due to the action of the ball valve 9 in closing port 10. Under some conditions, it may be desired to have the ignition chamber 11 momentarily open to the atmosphere at each explosion. For this purpose, a tubular nipple 23 may be threaded 100 into the housing 1 in alignment with the port-opening 21, said nipple being provided with a central bore 24 within which are disposed one or more balls 25, the outermost ball being adapted to operate as a valve in 105 110

the outer end of said nipple under a rising pressure in chamber 11 during the initial ignition of gas therein. According to this embodiment of our invention, the ignition mixture is supplied from the gaseous mixture in explosion cylinder 3, during the compression stroke of the engine. Thus, as the pressure rises in cylinder 3, a sufficient body of gas enters the chamber 11 through port opening 10 before said port is closed by the uppermost ball 9. At the same time, the closing of said port 10 maintains a pressure in chamber 11 at or about that of the atmosphere so that the sparking action between terminals 15 and 16 is greatly facilitated. For example, where the spark gap may ordinarily amount to but 1/32 of an inch, with the improved device according to our invention, this spark gap may be made as large as 1/4 of an inch. Furthermore, it thus becomes possible to make use of a leaner gas mixture both within the cylinder of the engine and within the ignition chamber 11, than would be the case where the pressure of the gas around the sparking terminals was as high as it becomes in the cylinder during compression. Upon ignition of the mixture in chamber 11, the resultant rapid expansion in said chamber forces the balls 9 downwardly, the flame escaping from chamber 11 into the cylinder 3, and thus effecting a rapid combustion of the main body of explosive mixture within cylinder 3.

Referring now to the embodiment of our invention shown in Figure 2, it will be understood that the conditions within chamber 11 are such as to produce only a small fraction of the usual heating effects about the terminals of the spark plugs. According to Figure 2, a modified form of spark plug is indicated at 26 said spark plug being provided with a lead wire 27 which is connected up with a terminal 28 within the ignition chamber 11 of the housing 1. According to the modified use of our device, as shown in this figure of the drawings, however, the ignition mixture may be introduced to chamber 11 from a separate source. Thus, for example, a tubular conveyor 29 may be employed in connection with a Stewart vacuum fuel feed tank, one end of said tube being connected by a coupling 30 with the outer end of a nipple 31, the outer end of said nipple being provided with a port-opening 32 which is adapted to be closed during the explosion by means of the outermost ball of a series of balls 33. A cotter pin 34 is arranged to prevent the inward movements of balls 33 and thereby prevents the closing of port-opening 21 into the chamber 11. According to this modified adaptation of our invention, the gaseous mixture entering through tube 29 may be of a different quality from that introduced to the explosion cylinder. During compression, the upper-

most ball 9 closes the port-opening 10 and is immediately thereafter forced downwardly under the ignition of the gaseous mixture in chamber 11 following which the main body of gas in cylinder 3 takes place as described above. 70

We claim:

1. An ignition device for internal combustion engines; said ignition device comprising a spark-plug, and a housing forming an 75 ignition chamber around the sparking terminals of said spark-plug, said housing being provided with an inlet port for explosive mixture, and a valve for controlling the admission of explosive mixture through said 80 inlet port.

2. The combination with a spark-plug attachment for internal combustion engines, said attachment being provided with an ignition chamber provided with a restricted 85 port, a valve for controlling the passage of explosive mixture through said port, sparking terminals arranged within said ignition chamber, and means for connecting said attachment to the cylinder of an internal 90 combustion engine.

3. An attachment for internal combustion engines, said attachment being provided with an ignition chamber and with a socket for receiving a spark-plug, the sparking terminals of said spark-plug being arranged within said ignition chamber, a tubular neck for connecting said attachment to the cylinder of an internal combustion engine, said attachment being provided with a port-opening 100 between said ignition chamber and the interior of said tubular neck, and a valve for said port-opening.

4. An attachment for internal combustion engines, said attachment being provided 105 with a socket for the reception of a spark-plug and with a hollow plug for connecting it to the cylinder of an internal combustion engine, said attachment being further provided with an ignition chamber for the reception of the sparking terminals of said spark-plug and with a valve-controlled port-opening between said ignition chamber and the interior of said hollow attachment plug. 110

5. In an ignition device for internal combustion engines, the combination with a terminal housing for spark-plugs, said housing being adapted to be connected to the cylinder of an internal combustion engine 115 and provided with an ignition chamber, of a spark-plug connected to said housing with the sparking terminals thereof disposed within said ignition chamber, said housing being provided with two port-openings, an 120 inwardly-closing valve for one of said port-openings, and an outwardly-closing valve for the other of said port-openings. 125

6. An attachment for spark-plugs, said attachment comprising a central body por- 130

tion provided with an ignition chamber, a threaded socket for the reception of a spark-plug, a tubular neck adapted to be threaded into the wall of an internal combustion cylinder, and with a valved port-opening between said tubular neck and said ignition chamber.

7. In an ignition device for internal combustion engines, the combination with a terminal housing for spark-plugs, said housing being provided with an ignition chamber, a tubular neck adapted to be threaded into the wall of a cylinder of an internal combustion motor, and a socket opening for the reception of a spark-plug, of a spark-plug threaded into said socket-opening with the sparking terminals disposed within said ignition chamber, said housing being provided with a port-opening between said ignition chamber and tubular neck, an inwardly-closing valve for said port-opening, and a conveyor tube for ignition mixture connected to said ignition chamber.

8. In an ignition device for internal combustion engines, the combination with a terminal housing for spark-plugs, said housing being provided with an ignition chamber, a tubular neck adapted to be threaded into the wall of a cylinder of an internal combustion motor, and a socket opening for the reception of a spark-plug, of a spark-plug threaded into said socket-opening with the sparking terminals disposed within said ignition chamber, said housing being provided with a port-opening between said ignition chamber and tubular neck, an inwardly-closing valve for said port opening,

and a conveyor tube for ignition mixture connected to said ignition chamber, said conveyor for ignition mixture being provided with a valved port-opening adapted to be closed under pressure developed in said chamber during ignition.

9. In an ignition device for internal combustion engines, the combination with a terminal housing for spark-plugs, said housing being provided with an ignition chamber, a tubular neck adapted to be threaded into the wall of a cylinder of an internal combustion motor, and a socket opening for the reception of a spark-plug, of a spark-plug threaded into said spark-plug socket opening with the sparking terminals thereof disposed within said ignition chamber, said housing being provided with a port-opening between said ignition chamber and tubular neck, a ball-guiding yoke threaded into said tubular neck, and a ball-valve movable in said yoke into and out of position to close said port-opening.

10. An attachment for spark-plugs, said attachment comprising a central body portion provided with an ignition chamber and a threaded socket for the reception of a spark-plug, a tubular neck adapted to be threaded into the wall of an internal combustion cylinder, said tubular neck being provided with a valved port-opening in communication with said ignition chamber, a yoke threaded into said tubular neck, and a ball-valve movable in said yoke into and out of position to close said port-opening.
